(57) **CLAIM**

The ornamental design for a frame for a versatile universal gym, as shown and described.

DESCRIPTION

FIG. 1 provides a front perspective view of a frame for a versatile universal gym showing my new design.

FIG. 2 provides a right-side elevation view thereof.

FIG. 3 provides a left-side elevation view thereof.

FIG. 4 provides a top plan view thereof.

FIG. 5 provides a bottom plan view thereof.

FIG. 6 provides a front elevation view thereof; and,

FIG. 7 provides a back elevation view thereof.

The features shown in broken lines represent environmental subject matter that are for illustrative purposes only and form no part of the claimed design.

1 Claim, 3 Drawing Sheets
